Primary Examiner — Katrina N Gonzalez

(57) **CLAIM**

The ornamental design for a seed guard for bird feeder as shown and described.

DESCRIPTION

FIG. 1 is a perspective view of a first embodiment of a seed guard for bird feeder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second embodiment of the seed guard for bird feeder;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of a third embodiment of the seed guard for bird feeder;

FIG. 18 is another perspective view thereof;

FIG. 19 is a front elevational view thereof;

FIG. 20 is a rear elevational view thereof;

FIG. 21 is a left side elevational view thereof;

FIG. 22 is a right side elevational view thereof;

FIG. 23 is a top plan view thereof;

FIG. 24 is a bottom plan view thereof;

FIG. 25 is a perspective view of a fourth embodiment of the seed guard for bird feeder;

FIG. 26 is another perspective view thereof;

FIG. 27 is a front elevational view thereof;

FIG. 28 is a rear elevational view thereof;

FIG. 29 is a left side elevational view thereof;

FIG. 30 is a right side elevational view thereof;

FIG. 31 is a top plan view thereof; and,

FIG. 32 is a bottom plan view thereof.

(Continued)

The broken lines in the drawings depict portions of the seed guard for bird feeder that form no part of the claimed design.
